PREVENTION OF FOAMING IN STEAM
GENERATION

Carl E. Johnson, Westchester, Ill., assignor to
National Aluminate Corporation, Chicago, Ill.,
a corporation of Delaware

No Drawing. Application August 14, 1948,
Serial No. 44,392

16 Claims. (Cl. 252—321)

1

The present invention relates to improved antifoaming compositions which are added to water that is subjected to boiling, as in the boilers of locomotives, stationary steam generators, evaporators, and in other instances where the boiling of water occurs, especially under superatmospheric temperature and pressure conditions, whereby the tendency of the water therein to foam is prevented or reduced and the boiling characteristics of the water so improved that priming of the steam generator and carryover of boiler water with the steam therefrom is prevented.

It is well known that in the operation of steam boilers, such as in railroad locomotives, in electric power plants and the like, or in other boiling operations where steam is formed, as for example in evaporators, that the water therein, even though initially it shows little tendency to foam, will when the amount of total dissolved solids approaches a relatively high concentration due to the production of steam, develop a very decided tendency to foam. This foaming of the water in a boiler producing steam is characterized not only by an accumulation of relatively stable froth or foam on the surface of the boiler water but also by the formation at the heat transfer surfaces in the boiler of extremely small steam bubbles. These minute bubbles show almost no tendency to coalesce and the result is that the entire volume of water in the steam generator is lifted in the form of so-called "light water," which is actually an intimate mixture of boiler water and tiny steam bubbles. When this occurs, considerable quantities of boiler water are physically carried out of the boilers or evaporators with the steam, thereby introducing solid matter into the steam lines and into the eventual condensate. Such carryover has many disadvantages because it tends to contaminate and restrict the steam lines, to plug or corrode the valves, to deposit on turbine blades, to plug and cause burning out of superheater tubes, and under serious conditions may even impair the cylinders and piston rods of steam engines or otherwise render the steam unfit for use. The carryover is frequently due in part, at least, to priming, or what may be described as surging or boiling over of the water.

Attempts have been made in the past to control foaming and priming by controlling the dissolved solids content of the water as by excessive blow-down of the boiler, that is, the removal, either continuously or periodically, of a portion of the boiler water containing the undesired ex-

cess solids. Also, it has been common to add materials for the purpose of abating the foam as by the injection of such materials as castor oil, talc, and the like. While these fatty materials, notably castor oil, have some small degree of efficiency, they are, on the other hand, quite deficient in that they introduce new difficulties which, in some instances, are worse than the conditions they are intended to cure. In the first place, these fatty materials or glycerides are very unstable under severe hydrolytic conditions encountered in steam generation, particularly under the conditions of superatmospheric pressure, the corresponding high temperatures and the alkalinity of the boiler water. The resultant decomposition products which remain in the boiler tend to increase the foaming tendencies of the boiler water and to accumulate in such a way as to give a "compound dirty" boiler, necessitating frequent washing. Furthermore, in many instances certain of the decomposition products thus produced, or sometimes even the materials themselves, have a definite volatility with steam and will, therefore, steam-distill out of the steam generators, thus appearing in the steam and in the eventual condensate. This, of course, is also undesirable. Additionally, such types of antifoaming agents usually are of such a low order of efficiency that they have to be employed in relatively large quantities, adding not only to the expense but also to the inconvenience of operating the steam generators; and since they are so unstable their effectiveness is of short duration, necessitating the continual charging into the boilers or other steam generators of relatively large amounts of these older antifoaming agents.

The most noteworthy advance over the use of the fatty glycerides described above was the discovery and development of certain high molecular weight substituted polyamides, which antifoaming compounds overcame many of the disadvantages of the former, especially in that they were highly efficient at lower dosage levels and much more resistant to decomposition, so that their effective life was relatively greater.

One of the objects of this invention is to provide a new and improved process for preventing the foaming and priming of steam generators, thus improving the quality of the steam produced thereby.

Another object is to provide new and improved compositions for adding to the water in a steam generator to prevent or reduce its tendency to foam.

Another object is to provide antifoaming com-

positions which are effective to prevent foaming when used in very low dosages.

A further object is to provide highly effective antifoam compositions which are readily and easily dispersible when added to the feed water entering a steam generator.

Another object of this invention is to provide antifoam compositions in which the active effective ingredients are readily soluble in water at relatively low temperatures, (e. g. 75 degrees F.) but decrease in solubility when the water is heated to relatively high temperatures such as are employed in the generation of steam under super-atmospheric pressures and the corresponding temperatures.

Still another object of invention is to provide a process of generating steam and new and improved antifoam compositions therefore wherein the period of effectiveness of the antifoam composition is greatly prolonged as compared to the period of effectiveness of other antifoam compositions presently known in the art.

Still another object of the invention is to provide a new and improved process of inhibiting foaming during steam generation which permits operations at higher dissolved solids contents than has heretofore been considered possible.

An additional object is to provide new and useful antifoaming compositions of an extremely high order of resistance to decomposition under the conditions prevailing in steam generation. Other objects will appear hereinafter.

In accordance with this invention, it has now been discovered that there is a series of compounds that are very effective when used as antifoaming and antipriming agents in steam generators and which may be broadly designated as high molecular weight diethers of polyoxyalkylene glycols, characterized by the presence in the polyoxyalkylene chain of one or more oxymethylene groups. These diethers possess several important advantages over formerly known antifoam compositions. They are all much more effective than any of the fatty glycerides, and many are more effective than any hitherto known materials. Furthermore, they are much more stable to decomposition under conditions of use than any of the glycerides or polyamides, thus giving them a greatly prolonged period of effectiveness in preventing foaming. In general, they are more readily dispersed in the water being fed to the steam generator than are older materials, and a further advantage offered by many of these diethers is that they are liquids or very low-melting waxy materials which are readily soluble at ordinary temperatures.

The diethers preferably employed in the practice of this invention may be represented by the structural formula

wherein R and R' are selected from the group consisting of alkyl, aryl, and aralkyl radicals; and X is a polyoxyalkylene chain selected from the group consisting of:

wherein E is hydrogen or an alkyl or aryl radi-

cal, n is an integer equal to 2 or more, and may have several values in the same compound, x and z are integers of 2 or more, and y is an integer of 1 or more. Such compounds are thus seen to include diethers of polyoxyalkylene glycols, in the polyoxyalkylene chain of which appears at least one oxymethylene group, and in which there are also other (larger) oxyalkylene groups. By these "larger" oxyalkylene groups is meant oxyalkylene groups which are not oxymethylene. Examples of these larger oxyalkylene groups are oxyethylene ($-OCH_2CH_2-$), oxypropylene

CH₃

oxybutylene

CH₃ CH₃

CH₃ CH₃ C₂H₅

and oxyalkylenes of greater number of carbons such as oxypentamethylene, oxyhexamethylene, oxydecamethylene and higher homologues. The larger oxyalkylene groups present in the polyoxyalkylene chain may all be the same, or they may be different, so that several are present in the same chain. When the larger oxyalkylene groups are not all the same, they may occur in the chain in various proportions and in a random or irregular sequence, with respect to each other.

In order that these diethers of polyoxyalkylene glycols possess the property of efficiently preventing the foaming and priming of steam generators, they should be of relatively high molecular weight. The lower limiting value of molecular weight will vary somewhat with variations in the size of the terminal groups R and R' and with the nature of the oxyalkylene groups comprising the polyoxyalkylene chain, as explained more fully hereinafter, but will, in general, be intermediate between 500 and 1000.

As pointed out above, all of the materials employed in the practice of this invention have the common feature of being diethers of polyoxyalkylene glycols, in the polyoxyalkylene chain of which one or more unsubstituted oxymethylene, or substituted oxymethylene, groups occur. For purposes of more detailed discussion, however, it will be convenient to consider these diethers under four separate classifications.

The first classification which may be considered consists of the diethers having the general structural formula

wherein the symbols R, R', E, n, x, and y have the same significance assigned to them hereinbefore, with the additional provision that y may also be zero, in which case the general structural formula reduces to

Although each of the compounds employed in the practice of this invention might be prepared by a variety of synthetic routes, it will be convenient to further explain their nature by reference to certain preparative methods by which they may be obtained. These methods of preparation are merely intended to be exemplary, and should not be construed as limiting in any way.

For example, a diether of the formula shown

in (1) above may be prepared according to the following equation:

For the case where y is equal to zero, the above equation becomes:

For further illustration, a specific example of a preparation according to Equation 3 would be the following:

A specific example of a preparation according to Equation 4 is:

Other materials of this classification suitable for the practice of this invention may be prepared according to Equation 4 from dodecanol, polyoxyethylene glycol of average molecular weight 400, and trioxymethylene; dodecanol, polyoxyethylene glycol of average molecular weight 400, and acetaldehyde; hexadecanol, polyoxypropylene glycol of average molecular weight 400, and trioxymethylene; dodecanol, polyoxyethylene glycol of average molecular weight 600, and trioxymethylene; hexadecanol, polyoxyethylene glycol of average molecular weight 1000 and trioxymethylene; dodecanol, polyoxyethylene glycol of average molecular weight 1000, and trioxymethylene; dodecanol, polyoxyethylene glycol of average molecular weight 1540, and trioxymethylene; hexadecanol, polyoxyethylene glycol of average molecular weight 1540 and trioxymethylene; hexadecanol, polyoxyethylene glycol of average molecular weight 600, and trioxymethylene; hexadecanol, polyoxypropylene glycol of average molecular weight 750, and trioxymethylene; hexadecanol, polyoxypropylene glycol of average molecular weight 1200, and trioxymethylene; dodecanol, polyoxyethylene glycol of average molecular weight 300, and trioxymethylene; hexadecanol, polyoxyethylene glycol of average molecular weight 400, and benzaldehyde; dodecanol, polyoxyethylene glycol of average molecular weight 1000 and acetone; dodecanol, polyoxyethylene glycol of average molecular weight 1000 and propanal; dodecanol, polyoxyethylene glycol of average molecular weight 1000, and butanal; dodecanol, polypropylene glycol of average molecular weight 750, and phenylacetaldehyde; and hexadecanol, polyoxyethylene glycol of average molecular weight 400, and methyl ethyl ketone. In general it may be said that suitable compounds will result from the synthesis of Equation 4 where the aliphatic alcohol contains at least about 12 carbon atoms and the polyoxyalkylene glycol contains at least about 7 oxyalkylene groups. The aldehyde or ketone from which the unsubstituted oxymethylene or substituted oxymethylene group is derived may be chosen from a wide variety of such compounds, as shown by the examples, the principal requisite being that it will not undergo undesirable side reactions under the mildly acid conditions of the method. Thus, such aldehydes as crotonaldehyde and furfural undergo polymerization, etc.

under the influence of the acidic catalysts used (as is more fully explained hereinafter) and the yield of desirable diethers is thus reduced.

The synthetic procedure outlined in Equation 3 is especially applicable to low molecular weight alcohols such as methyl, ethyl, and propyl, and is further a convenient way of synthesizing compounds in which R contains an aryl radical. Thus, in Equation 3, if phenoxyethanol or phenylethanol were employed as ROH , the resulting diether would be aroxyalkyl or aryl, respectively. Diethers of this first classification, containing smaller R groups, are especially suitable for the practice of this invention when their molecular weight is at least about 2000 to 5000.

The second classification which may be considered consists of the diethers having the general structural formula

wherein, again, the symbols R , R' , E , n , and z have the same significance assigned to them hereinbefore. An exemplary method of preparing a compound of this classification may be represented by the equation:

A specific example of a synthesis according to Equation 8 is the following:

in which the monoether $\text{C}_4\text{H}_9\text{O}(\text{C}_n\text{H}_{2n}\text{O})_z\text{H}$ is the monobutyl ether of a polyoxyalkylene glycol containing both oxyethylene and oxypropylene groups in random arrangement and in which the weight ratio of ethylene oxide to propylene oxide is approximately 1:1, the molecular weight of the monobutyl ether being approximately 1000. Other specific examples of compounds falling within this classification and suitable for the practice of this invention are those which may be prepared according to the reaction of Equation 8 from benzyl alcohol, the monobutyl ether of Equation 9, and trioxymethylene; hexadecanol, the monobutyl ether of a polyoxyethylene glycol of average molecular weight 750, and trioxymethylene; dodecanol, the monobutyl ether of Equation 9, and acetaldehyde; octanol, the monobutyl ether of a polyoxypropylene glycol of average molecular weight 3000, and acetone; and dodecanol, the monobutyl ether of a polyoxypropylene glycol of average molecular weight 1000, and benzaldehyde. In fact, the limiting features appear only to be that the total molecular weight of the compound should be at least about 1000 and neither of the groups R or R' should be smaller than four carbon atoms. With these limitations, compounds prepared from a wide variety of alcohols, monoethers, and aldehydes or ketones have been found suitable for the practice of this invention.

A third classification which may be considered consists of diethers of the following structural formula:

wherein R , R' , E , n , and z have the same significance ascribed to them hereinabove. Specific examples of syntheses according to Equation 10 are the following:

wherein the monoether $\text{C}_4\text{H}_9\text{O}(\text{C}_n\text{H}_{2n}\text{O})_z\text{H}$ is the

same as that described hereinabove for Equation 9, and

Other suitable compounds falling within this classification and useful for the practice of this invention include those formed by aldehyde or ketone coupling of monoethers of polyoxyalkylene glycols of such character that the total molecular weight of the reaction product is at least approximately 500 when the terminal alkyl groups are of 12 or more carbon atoms, and preferably is at least 1000 or greater, the lower limiting molecular weight being greater for compounds having smaller terminal alkyl groups, say of four carbons. Suitable aldehydes and ketones are those stable under the reaction conditions, as discussed in detail hereinabove.

A fourth classification which may be considered consists of diethers of the following structural formula:

wherein R, R', E, n, x and z have the same significance as heretofore. A specific example of a synthesis leading to a compound of this classification is the following:

wherein the monobutyl ether $C_4H_9O(C_2H_4O)_xH$ is the same as described for Equation 9 and the polyoxyethylene glycol $HO(C_2H_4O)_xH$ is of average approximate molecular weight 6000.

A study of these compounds will reveal that they are related to those of the third classification, above, but instead of merely coupling two monoethers through an unsubstituted oxymethylene or substituted oxymethylene group, as in the compounds of the third classification, in these compounds there has been introduced an additional polyoxyalkylene chain between the two monoethers, by means of the oxymethylene bridges, thus obtaining greater molecular weight and chain length. In general, increased molecular weight contributes to the efficiency of anti-foaming materials. As indicated in the discussion of compounds of the third classification, higher molecular weight is especially desirable, and becomes particularly so, when the diethers are to contain two relatively small groups R and R'. Also, many monoethers of polyoxyalkylene glycols are readily available wherein the polyoxyalkylene chain is relatively short and coupling by means of the single oxymethylene group, to give compounds similar in structure to those of the third classification would lead to compounds of molecular weight below the lower limiting value. However, the introduction into the chain of a high molecular weight polyoxyalkylene chain derived from readily available polyoxyalkylene glycols will permit the use of these shorter chain monoethers to yield very efficient antifoam compositions.

For example, many of the methyl and ethyl monoethers of polyoxyethylene and polyoxypropylene glycols are available commercially, but the methyl and ethyl groups are of a size that when R or R' is composed of either of them, it is desirable, for efficient antifoam activity, that the intermediate polyoxyalkylene chain be of molecular weight in the neighborhood of at least 2000, depending somewhat on the nature of the oxyal-

ylene groups. The synthesis of Equation 14 permits use of these monoethers.

Likewise many monoethers of the type represented by phenoxyethoxyethanol, alkylphenoxyethoxyethanol, and corresponding compounds in which other oxyalkylene groups are inserted in the chain, may readily be used in the synthesis of Equation 14.

As stated hereinabove, the synthetic methods already described were chosen as being suitable ones for the preparation of the diethers under discussion. There are other suitable methods also and these will readily suggest themselves to one skilled in the art. As a single example of a method different from the ones described above, the following may be cited:

A polyoxyalkylene glycol is converted to the corresponding di-chloromethyl ether:

This di-chloromethyl ether may then be reacted with an alcohol:

Reference to the preceding discussion will show that this resulting diether is one falling within the first classification.

Similarly, the di-chloromethyl ether of Equation 15 may be reacted with a monoether of a polyoxyalkylene glycol:

Reference to the preceding discussion will show that this diether falls into the fourth classification.

Since as already stated it is possible to prepare the diethers of this invention by various routes, the invention should not be limited by the following descriptive discussion which is merely intended to illustrate in detail satisfactory procedures for the preparation of the materials suitable for employment within the scope of the present invention. The preparative method is based upon the fact that it is possible to link together two hydroxyl-containing molecules by means of a condensation with an aldehyde or a ketone whereby one molecule of water is eliminated with the formation of a methylene bridge between the oxygen atoms of the aforementioned hydroxyl-containing molecules. Conditions favoring this condensation are those which favor the removal of water from the reaction zone. Acid catalysts may also be employed, suitable examples of which are sulphuric acid, hydrochloric acid, ferric chloride, aluminum chloride, stannic chloride, and zinc chloride. The resulting formals, or substituted formals, are unstable in the presence of the acidic catalysts and, therefore, prior to the recovery of the product it is desirable to neutralize the acidic catalyst with some caustic material such as caustic soda, soda ash, lime, sodium acetate, etc.

The dehydration referred to may be carried out by the application of heat alone but is materially hastened and made more complete by operating under a vacuum or with gasification of the reacting mixture (e. g. by a stream of air, nitrogen, carbon dioxide or other suitable inert gases). It is preferably carried out through the use of a volatile inert solvent such as benzene, toluene

or xylene. In using the solvent type carrier to remove water the reaction between the hydroxyl-containing bodies and the aldehyde or ketone is carried out in the presence of the solvent under atmospheric pressure distillation conditions, the distillate being recovered and permitted to separate into two phases, the upper solvent phase being continually returned to the reaction vessel and the lower aqueous phase being discarded from the separator.

Following the above suggestions, the reaction of Equation 6 hereinabove is effected by heating the mixture of 2 moles of hexadecanol, 2 moles of trioxymethylene and 1 mole of commercial nonaethylene glycol in the presence of an approximately equal weight of benzene and with the addition of solid ferric chloride in a quantity equal to approximately 0.5% of the combined weight of the alcohol, glycol and aldehyde. Heating is carried out so that the benzene slowly distills from the reaction mixture carrying with it the water formed. The distillate is collected in a conventional water trap, the water separated and the benzene returned to the reaction vessel. When the water collected is equivalent to the theoretical amount expected from the reaction, the acidic catalyst (ferric chloride) is neutralized by the addition of a slight excess of solid, pulverized sodium acetate and the benzene is distilled leaving the reaction product behind as a viscous liquid which tends to partially solidify upon cooling. If desired, the product may be filtered while hot.

In general the above mode of operation, using approximately the stoichiometrical quantities of reactants, may be applied to the preparation of any of the compounds described hereinabove. The acid catalysts may be used in a range of 0.3 to 1.0% by weight based on the total weight of the reactants exclusive of any dehydrating solvent. The dehydrating solvent may be chosen from a variety of such solvents and by varying the boiling point and the pressure under which the reaction is carried out these reactions may be effected at any temperature within the range of about 50° to 150° C. Frequently because of some loss of aldehyde or ketone during the distillation, it is desirable to use a slight excess of this reactant and in some cases to add it portion-wise to the reaction mixture. Furthermore, in carrying out a reaction of the type illustrated in Equation 3, it is desirable to add the alcohol (ROH) after the reaction between the aldehyde or ketone and the polyoxyalkylene glycol has proceeded for some time.

The products hereinabove described may be liquid or low-melting wax-like solids, and in some cases may be rather hard solids which may be pulverized by grinding. They may be entirely soluble in cold water or only partially soluble. In the latter case, they are relatively easily dispersed in the feedwater by means of additional dispersing agents, as described below. All of the products exhibit substantial insolubility in hot water, the phenomenon of decreasing solubility in water with increasing temperature being characteristic of compounds of this class which contain multiple ether linkages and in which the ratio of ether linkages to carbon is sufficiently great to permit the weak hydrogen bonding effect of the ether oxygen to confer water solubility.

The amounts of an antifoam agent employed in inhibiting the foaming of water in a steam generator will depend upon several factors, among them the per cent of solids in the foaming liquid,

the nature of the solids, the alkalinity, temperature, and pressure, the type and degree of circulation in the steam generator, the rate of steam production, and the amount of foam suppression desired. It is, therefore, impossible to state any rigid rules for estimating the amount of an antifoam which needs to be used. The amounts of the diethers of this invention which are required are, however, extremely small. For many purposes, amounts of the order of 0.01 grain per gallon to 0.02 grain per gallon in the feedwater are sufficient, and under certain conditions quantities as low as 0.001 grain per gallon in the feedwater have proved effective. In general, it can be said that quantities greater than 0.1 grain per gallon in the feedwater would seldom be required.

By way of illustrating the remarkable effectiveness of the diethers of this invention, the method of testing their antifoam efficiency in the laboratory will be described and exemplary data given.

In the laboratory, the experimental boiler used was of the type described in the publication "Solid Matter in Boiler Water Foaming," by Foulk and Brill, which appeared in the periodical Industrial and Engineering Chemistry, volume 27, pages 1430-35. This boiler was fitted with sight glasses on each side of the steam release space so that conditions in the boiler in a zone several inches above and below the normal water level were observed while the boiler was operating under pressure. It was also equipped with an automatic water level control which held the water level within a range of ± 0.25 inch.

In the series of experiments described below, a feedwater was used having the following composition, expressed in parts per million, by weight:

Calcium hardness (as CaCO_3)	154.0
Magnesium hardness (as CaCO_3)	154.0
Alkalinity (methyl orange) (as CaCO_3)	726.0
Sodium chloride (as NaCl)	85.5
Sodium sulfate (as Na_2SO_4)	718.0
Tannin extract, dry	34.2

To this feedwater was added the antifoam composition of the character and in the quantity specified in the specific experiment, and this water was then gradually concentrated in the test boiler by evaporation at the rate of six gallons per hour at 250 pounds per square inch (p. s. i.) gauge pressure. A continual recording was made of the relative conductivity of the condensate from the boiler, and continual observations were made of the character of the boiling and the amount of foaming as seen through the sight glasses. When the antifoam thus introduced continuously with the feedwater was no longer able to overcome the foaming tendencies brought about by the concentration of dissolved solids in the boiler water, the foam height became great enough to cause boiler water to be carried out of the boiler with the steam, and this end-point of the test was determined both by observation through the sight glasses and, particularly, by the abrupt increase in the conductivity of the steam, as shown in the continuous recorder. At this end-point, a sample of the boiler water was withdrawn from the boiler and analyzed, and the effectiveness of the antifoam expressed in terms of the total dissolved solids concentration which it permitted the boiler to carry. A high value of total dissolved solids (TDS) indicates an effective antifoam. With no antifoam, this feedwater gives a carryover at a total dissolved solids value of approximately 175 grains per gallon.

11

Test I

An antifoam composition was prepared by the reaction of a polyoxyethylene glycol of average molecular weight 900, octyl alcohol, and trioxymethylene in a molecular ratio of 6:1:6, using benzene and ferric chloride as outlined above. After neutralization of the catalyst, removal of the benzene, and filtration, the product cooled in the form of a brittle brown wax. It was soluble in cold water and was added to the feedwater at a dosage of 0.005 grain per gallon. Carryover did not occur until the total dissolved solids concentration in the boiler water had reached 3637 grains per gallon. The active antifoam ingredient is believed to have a structure represented by Formula 1 above.

Test II

A compound corresponding to the general formula given as (2), above, was prepared from polyoxyethylene glycol of average molecular weight 400, hexadecanol, and trioxymethylene in a mole ratio of 1:2:2.6, using benzene and ferric chloride. After neutralization of the catalyst by potassium acetate, removal of the benzene, and filtration, the product cooled to a mushy semi-solid. A dry-appearing, pulverized composition was made up by mixing 3 grams of the semi-solid diether with 1 gram of oleic acid and 1 gram of dipropylene glycol and grinding the resulting liquid mixture into 95 grams of a dry, pulverized lignin derivative commonly used in boiler water treatment, and made by desulfonation and partial depolymerization of sodium lignin sulfonate by treatment with aqueous alkali at high temperatures. This material exhibits an excellent dispersing effect on the diethers but neither it, nor the oleic acid or dipropylene glycol, of themselves, exert an antifoam effect in the boiler. The dry, pulverized antifoam composition, containing 3% of the diether, was added to the feedwater at a dosage of 0.167 grain per gallon, resulting in a concentration of the diether in the feedwater of 0.005 grain per gallon. This permitted a total dissolved solids concentration in the boiler of 2747 grains per gallon before carry-over occurred.

Test III

A compound of the type represented by Formula 7, above, was prepared from benzyl alcohol, trioxymethylene, and the monobutyl ether of a polyoxyalkylene glycol containing both oxyethylene and oxypropylene groups in the chain in a weight ratio of approximately 1:1, and having a total average molecular weight of about 1000. The mole ratio of the three reactants was 1:1:1. When finished, the product was a liquid which was formulated into a dry-appearing, pulverized composition exactly as was done in the case of the diether of Test II. The pulverized composition, containing 3%, by weight, of the diether, was added to the feedwater at a dosage of 0.167 grain per gallon, resulting in a concentration of the diether in the feedwater of 0.005 grain per gallon. This permitted a total dissolved solids concentration in the boiler water of 558 grains per gallon before carryover.

Test IV

A compound of the type represented by Formula 10, above, was prepared by reacting two molecular portions of the monobutyl ether described in Test III with one molecular portion of trioxymethylene in boiling benzene, in the pres-

12

ence of a small amount of ferric chloride as catalyst. The resulting diether was a liquid and was mixed with dipropylene glycol and the lignin derivative of Test II in a weight ratio of 3:1:96, respectively. The resulting pulverized composition, containing 3%, by weight, of the diether, was added to the feedwater in a dosage of 0.167 grain per gallon, resulting in a concentration of the diether in the feedwater of 0.005 grain per gallon. This permitted a total dissolved solids concentration in the feedwater of 697 grains per gallon before carryover.

Test V

A compound having the structure represented by Formula 13, above, was prepared from the monobutyl ether described in Test III, a polyoxyethylene glycol of average molecular weight 6000 ("Carbowax 6000"), and trioxymethylene in a molecular ratio of 2:1:2, respectively, using benzene and ferric chloride. The diether, when finished, was a light brown wax, soluble in cold water. It was added to the feedwater at a dosage of 0.005 grain per gallon, and permitted a total dissolved solids concentration in the boiler in excess of 3198 grains per gallon, the test being stopped with no carryover.

One of the difficulties of using most antifoam materials is that of conveniently introducing them into the water in small, controlled amounts so that their maximum effectiveness is utilized. While many of the diethers employed in accordance with this invention are readily soluble in cold water, others are not completely soluble and must be rendered readily dispersible for use. Liquids, waxes, and preformed emulsions are inconvenient to apply to the feedwaters used by locomotives and other power plants. It is thus a further object of this invention to provide the diethers compounded with other water treating chemicals in a powdered or briquetted form which can readily and conveniently be added to water, and which will disperse in the water quickly without excessive agitation or mixing.

The diethers employed in the practice of this invention can all be incorporated into dry powdered materials such as powdered tannin, sodium lignin sulfonate, the desulfonated lignin described in Test II hereinabove, soda ash, various orthophosphates and polyphosphates. Depending somewhat upon the powdered absorbent selected, amounts of the diethers of the order of 5 to 10% of the total composition may be readily incorporated to give a dry-appearing pulverized product. By the use of suitable binders and other well-known techniques, such compositions may also be briquetted.

The resulting dry-appearing products just described are readily and completely dispersible in water when the diethers themselves are soluble or dispersible. When diethers are employed which are substantially insoluble in water, these, too, give dry-appearing compositions by the method described if a dispersing agent is used in conjunction with them. In fact, many of the common water treating chemicals of a tannin or lignin nature behave as sufficiently powerful dispersants to readily disperse the insoluble diethers in the form of a relatively stable aqueous dispersion. Where it is not desired to use the tannins or lignin derivatives in quantity sufficient to act as dispersants for the diethers, a small amount of soap, such as the alkali metal soaps of oleic acid or tall oil, or a sulfonated oil, may be employed with good results, and the amount of soap or sulfonate thus required is insufficient to interfere

with the powerful antifoam effect of the diethers or to render the boiler "compound dirty."

In general, then, the diethers of this invention may be prepared in the form of dry-appearing pulverized or briquetted compositions which are readily and completely dispersible in water with a minimum of agitation by incorporating them, with or without a dispersant such as soap or sulfonated oil, with various tannins, lignins, or other pulverized chemicals, either alone or in combination.

The practice of the invention is applicable to the inhibition of foaming in steam generation over a relatively wide pressure and temperature range. In locomotive boilers, steam is generally generated at pressures around 250 pounds per square inch and the corresponding temperatures. Excellent results have been obtained with the practice of the invention at pressures within the range of 100 to 300 pounds per square inch and the corresponding temperatures. The invention can also be used, however, in connection with the generation of steam at much higher pressures and the corresponding temperatures, as, for example, in stationary boilers operating at pressures as high as 1000 to 1500 pounds per square inch. The compositions employed in accordance with the invention are effective not only in inhibiting foaming but also in conditioning and improving the quality of the steam. For this purpose, they may be used in even smaller amounts than the amounts required for the complete inhibition of foaming and priming.

The diethers employed in the practice of this invention are desirably used in conjunction with other organic water treating chemicals of the tannin and lignin types in treating many water supplies as will be seen from the following. On waters high in magnesium salts in which the magnesium in the boiler will generally be in the form of magnesium hydroxide, it is desirable that sufficient of hydroxylated organic material such as tannins, tannic acid, gallic acid, pyrogallol, catechol, phloroglucinol, etc. be added along with the diethers. These hydroxylated organic compounds have the ability of nullifying the bad effects of the magnesium hydroxide. Magnesium hydroxide appears to partially selectively adsorb the antifoam material and so take it out of the boiler water so that the full antifoam action cannot be exerted by the antifoam compositions when in this adsorbed state. However, when an organic material such as a tannin is added, magnesium hydroxide appears to lose its ability to interfere with the antifoam action. Inasmuch as most boiler feedwaters encountered will have varying amounts of magnesium salts present, it is desirable that such hydroxylated organic compounds be mixed with the diethers prior to addition to the boiler feedwater.

Thus another advantage is evident in preparing and using the pulverized or briquetted compositions hereinabove described containing both the diether antifoam and the polyhydroxylated organic material of the tannin or lignin-derivative type.

As will be apparent from the foregoing description, the compounds employed in accordance with the invention do not all give the same results and from that standpoint are not necessarily equivalents. Some of these diether compositions, especially those of the type referred to in Test I, are truly remarkable in their foam inhibiting properties even when compared with the best of the antifoam compositions which have been previously used commercially.

The term "an oxymethylene group" unless modified by the words "unsubstituted" or "substituted" is intended to cover generically the group

10 where A and B may be hydrogen or carbon radicals, e. g., alkyl or aryl radicals. An unsubstituted oxymethylene group is one in which both A and B are hydrogen atoms. A substituted methylene group is one in which A or B or both is a carbon radical in which a carbon atom is linked to the main methylene group.

15 A preferred class of compounds for employment in accordance with the invention is that derived by the reaction of an aldehyde or a ketone with a monohydric alcohol and a member 20 from the group consisting of monoethers of polyoxalkylene glycols and polyoxalkylene glycols, wherein the compound is at least partially soluble 25 in water at room temperatures of say 75° F. and decreases in solubility to substantially water insolubility upon heating to steam generating temperatures.

The invention is hereby claimed as follows:

30 1. A process of minimizing the production of foam in and the priming of steam generators operating under superatmospheric pressure conditions which comprises incorporating with a water therein containing an amount of total solids tending to produce foaming and priming a minor quantity of a diether of a polyoxalkylene 35 glycol characterized by a total average molecular weight of at least 500 and a chemical structure in which the polyoxalkylene chain contains at least one oxymethylene group, said diether being substantially insoluble in said water under said steam generating conditions and said quantity being sufficient substantially to inhibit foaming and priming.

40 2. A process as claimed in claim 1 in which the quantity of said polyoxalkylene glycol incorporated into the water is within the range of 0.001 grain to 0.1 grain per gallon of water.

45 3. A process as claimed in claim 1 in which the steam is generated at pressures within the range of 100 to 1500 pounds per square inch and the corresponding temperatures.

50 4. A process as claimed in claim 1 in which a steam is generated at pressures within the range of 100 to 300 pounds per square inch and the corresponding temperatures.

55 5. A process of minimizing the production of

foam in and the priming of steam generators operating under superatmospheric pressure conditions which comprises incorporating with a water therein containing an amount of total solids tending to produce foaming and priming a quantity of a diether of a polyoxalkylene glycol characterized by an average molecular weight of at least 500, and a chemical structure in which the polyoxalkylene chain contains at least one

60 unsubstituted oxymethylene group and higher oxalkylene groups having not more than three carbon atoms, said diether being substantially insoluble in said water under said steam generating conditions and said quantity being sufficient substantially to inhibit foaming and priming.

65 70 75 6. A process of minimizing the production of foam in and the priming of steam generators operating under superatmospheric pressure conditions which comprises incorporating with a water therein containing an amount of total solids

15

tending to produce foaming and priming a quantity of a diether of a polyoxyalkylene glycol having the following structural formula:

wherein R and R' are from the group consisting of alkyl, aryl and aralkyl, E is from the group consisting of hydrogen, alkyl and aryl, n and x are integers of at least 2, y is from the group consisting of O an integer, and the average molecular weight is at least 500, said diether being substantially insoluble in said water under said steam generating conditions and said quantity being sufficient to substantially inhibit foaming and priming.

7. A process of minimizing the production of foam in and the priming of steam generators operating under superatmospheric pressure conditions which comprises incorporating with a water therein containing an amount of total solids tending to produce foaming and priming a quantity of a dialkyl ether of a polyoxyalkylene glycol containing in the polyoxylalkylene chain at least two unsubstituted oxymethylene groups and a plurality of larger oxyalkylene groups, the number of carbon atoms in the terminal alkyl ether groups not exceeding 4 and the average molecular weight of said dialkyl ether derivatives being within the range from 2000 to 5000, said quantity being sufficient to substantially inhibit foaming and priming.

8. A process of minimizing the production of foam in and the priming of steam generators operating under superatmospheric pressure conditions which comprises incorporating with a water therein containing an amount of total solids tending to produce foaming and priming 0.001 to 0.1 grain per gallon of said water of the product of the reaction at temperatures within the range of the reaction at temperatures within the elimination of water of 2 moles of an aliphatic alcohol containing at least 12 carbon atoms, 1 mol of a polyoxyalkylene glycol containing at least 7 oxyalkylene groups from the group consisting of oxyethylene and oxypropylene groups, and 2 moles of formaldehyde.

9. A process of minimizing the production of foaming in and the priming of steam generators operating under superatmospheric pressure conditions which comprises incorporating with a water therein containing an amount of total solids tending to produce foaming and priming a quantity of a diether of a polyoxyalkylene glycol having the general formula

wherein R and R' are from the group consisting of alkyl, aryl and aralkyl, neither R nor R' containing less than 4 carbon atoms, E is from the group consisting of hydrogen, alkyl and aryl, n and x are integers of at least 2, and the average molecular weight is at least 1000, said diether being substantially insoluble in said water under said steam generating conditions, and said quantity being within the range of 0.001 to 0.1 grain per gallon of water treated.

10. A process of minimizing the production of foam in and the priming of steam generators operating under superatmospheric pressure conditions which comprises incorporating with a water therein containing an amount of total solids tending to produce foaming and priming 0.001 to 0.1 grain per gallon of said water of the product of the reaction at temperatures within the range of 50 degrees C. to 150 degrees C. with

16

the elimination of water of 1 mol of an alcohol containing at least 4 carbon atoms, 1 mol of a monoalkyl ether of a polyoxyalkylene glycol in which the said monoalkyl group contains at least 5 4 carbon atoms and the polyoxyalkylene chain contains both oxyethylene and oxypropylene groups in random arrangement and in the weight ratio of ethylene oxide to propylene oxide of approximately 1:1, and 1 mole of formaldehyde.

11. A process of minimizing the production of foaming in and the priming of steam generators operating under superatmospheric pressure conditions which comprises incorporating with water therein from which the steam is generated 15 a minor quantity of a diether of a polyoxyalkylene glycol having the following general formula

wherein R and R' are from the group consisting of alkyl, aryl and aralkyl, E is from the group consisting of hydrogen, alkyl and aryl, n and x are integers of at least two and the average molecular weight is at least 1000, said diether being substantially insoluble in said water under 20 said conditions of steam generation, and said quantity being sufficient to substantially inhibit foaming and priming.

12. A process of minimizing the production of foam in and the priming of steam generators operating under superatmospheric pressure conditions which comprises incorporating with water therein from which the steam is generated 30 a minor quantity of a diether of a polyoxyalkylene glycol having the general formula

wherein R and R' are from the group consisting of alkyl, aryl and aralkyl, E is from the group consisting of hydrogen, alkyl and aryl, and n, x and z are integers of at least 2, said diether having an average molecular weight of at least 500 and being substantially insoluble in said water under 40 said conditions of steam generation, and said quantity being sufficient to substantially inhibit forming and priming.

13. A process of minimizing the production of foam in and the priming of steam generators operating under superatmospheric pressure conditions which comprises incorporating with a water therein containing an amount of total 50 solids tending to produce foaming and priming 0.001 to 0.1 grain per gallon of said water of the product of the reaction at temperatures within the range of 50 degrees C. to 150 degrees C. with the elimination of water of 2 moles of a monoether of a polyoxyalkylene glycol, 1 mole of a polyoxyalkylene glycol and 2 moles of formaldehyde, the oxyalkylene groups in said monoether and said polyoxyalkylene glycol being from the group consisting of oxyethylene and oxypropylene groups, said quantity being sufficient to substantially inhibit foaming and priming.

14. A method of generating steam from a boiler water having a tendency to foam on boiling and which contains magnesium compounds, which comprises dispersing in said water a quantity of a diether of a polyoxyalkylene glycol characterized by a total average molecular weight of at least 500 and a chemical structure in which the polyoxyalkylene chain contains at least one oxymethylene group, said diether being substantially insoluble in said water under steam generating conditions, and a quantity of a hydroxylated organic compound from the group consisting of tannins, sodium lignin sulfonate and desulfonated lignins effective to nullify the

action of the magnesium compounds on said diether, the quantity of said diether being effective to inhibit the tendency of said water to foam on boiling, and heating the resultant aqueous dispersion to the boiling point.

15. The method of generating steam from a boiler water having a tendency to foam on boiling and which contains magnesium compounds, which comprises dispersing in said water a quantity of a diether of a polyoxyalkylene glycol characterized by an average molecular weight of at least 500 and a chemical structure wherein the polyoxyalkylene chain consists of at least one oxymethylene group and higher oxyalkylene groups having not more than 3 carbon atoms, said diether being substantially insoluble in said water under steam generating conditions, and a quantity of a hydroxylated organic compound from the group consisting of tannins, sodium lignin sulfonate and desulfonated lignins effective to nullify the action of the magnesium compounds on said diether, the quantity of said diether being effective to inhibit the tendency of said water to foam on boiling, and heating the resultant aqueous dispersion to the boiling point. 25

16. The process of generating steam from a water having a tendency to foam on boiling which comprises dispersing in said water a quantity of a dialkyl ether of a polyoxyalkylene glycol containing in the polyoxyalkylene chain at least one oxymethylene group and a plurality of larger oxyalkylene groups from the group consisting of oxyethylene and oxypropylene, said dialkyl ether being substantially insoluble in said boiler water under steam generating conditions, the average molecular weight of said dialkyl ether derivative being at least 500 and said quantity being effective to inhibit the tendency of said water to foam on boiling, and heating the resultant aqueous dispersion to the boiling point.
